NEWSPAPER AND MAGAZINE RACK

Thomas F. Lee, Houston, and Rollie M. Wheeler, Jr.,
Port Arthur, Tex.

Application September 2, 1955, Serial No. 532,303

4 Claims. (Cl. 211—106)

This invention relates to improvements in racks or holders for newspapers, magazines, and the like.

The general desirability of a rack of the type stated is well appreciated, and heretofore, it has been proposed to provide tubular holders, connectable to support posts in front of a house, for receiving a delivered newspaper. Other devices have also been conceived for the purpose of receiving delivered magazines, mail, or newspapers, but in many instances they do not function with full efficiency in supporting the article in a manner to insure against its being torn, or alternatively, are difficult to attach to the side or front of a house or similar building, or to a fence post.

The main object of the present invention is to provide a generally improved newspaper or magazine rack, which can be manufactured at a minimum of cost, from a single length of spring wire, for holding such as newspapers in flat condition and under tension.

A further object of importance is to provide a device of the character indicated above which is especially devised for easy and secure attachment to and stable mounting on supports, such as a wall, a gate, a gate post, or the like.

Other objects of the invention will appear from the following description, and the annexed drawings, in which like reference characters designate like parts throughout the several views, and wherein:

Figure 1 is a front perspective view of a rack formed according to the present invention;

Figure 2 is a top plan view;

Figure 3 is a rear elevational view; and

Figure 4 is a vertical sectional view on line 4—4 of Figure 3.

The illustrated rack is formed from a single length of stout, relatively rigid spring wire. The intermediate portion of said length of wire is bent to provide an inverted V-shaped holding member having a pair of upwardly converging straight legs 10 merging at their upper ends into a forwardly and downwardly curved handle loop 12.

At their lower ends the legs 10 merge into short, horizontally disposed rearwardly extending arms 14 which merge at their rear ends into the lower ends of single vertical rear legs 16. The legs 16, as shown in Figure 3, converge slightly in an upward direction, and the upper ends of the legs 16 are spaced from opposite sides of the handle loop 12, and are on a level slightly above the handle loop 12.

At their upper ends the rear legs 16 merge into downwardly and laterally inwardly declining arms 18, which merge at their lower ends into laterally outwardly projecting substantially horizontal arms 20 provided on their free ends with attaching eyes 22. As shown in Figures 2 and 3, the lower portions of the arms 18 and the inner ends of the arms 20 extend across the rear sides of the related front legs 10 and are spaced from each other crosswise of the device. The eyes 22 are located directly

2

behind the rear legs 16. The arms 18 and 20 are angulated laterally inwardly and forwardly away from the rear legs 16, and the juncture 21 of these arms provide abutments for newspapers and the like placed between the holding member and the abutments.

The abutments 21 are spaced from each other crosswise of the device.

In use of the device, screws 24 or the like are adapted to be extended through the eyes 22, to secure the device 10 fixedly against the vertical supporting surface S, which may be the side of a house, gate post, or the like. When the device is secured in this manner, an article such as a magazine or newspaper can be placed therein, by pulling forwardly on the handle loop 12, that is, to the right in Figure 4. This swings the legs 10 forwardly from the abutments 21 and from the supporting surface S, so as to provide sufficient space between the holding member and the abutments 21 for reception of an article, with the article resting upon the short arms 14.

The wire used in forming the device has a slightly springable characteristic, sufficient to permit the legs 10 to be pulled forwardly against the inherent spring tension thereof, and when the handle loop 12 is released, the holding member returns toward the abutments 21 and the rear legs 16 as to clamp the article therebetween. It is to be observed that only rounded or flat surfaces are in engagement with the article, both during the insertion and the removal thereof from the rack. As a result, the article will not be torn when it is removed or inserted, and yet, while supported in the device, is firmly gripped to prevent its accidental removal.

It is believed apparent that the invention is not necessarily confined to the specific use or uses thereof described above since it may be utilized for any purpose to which it may be suited. Nor is the invention to be necessarily limited to the specific construction illustrated and described, since such construction is only intended to be illustrative of the principles it being considered that the invention comprehends any minor change in construction that may be permitted within the scope of the appended claims.

What is claimed is:

1. In a rack of the character described, a holding member comprising a pair of front legs having lower ends and upper ends, a handle loop connecting and extending forwardly from the upper ends of the front legs, rearwardly extending horizontal arms on the lower ends of the front legs, said horizontal arms having rear ends, vertical rear legs having upper ends and lower ends, the rear ends of the horizontal arms being secured to the lower ends of the rear legs, the upper ends of the rear legs being laterally spaced from said handle loop, laterally inwardly and downwardly declining arms on the upper ends of the rear arms, said declining arms having lower ends disposed behind said front legs, lateral outwardly projecting arms on the lower ends of the declining arms, said lateral arms having free laterally outward ends having attaching eyes thereon disposed behind the rear legs.
2. In a rack of the character described, a holding member comprising a pair of front legs having lower ends and upper ends, a handle loop connecting and extending forwardly from the upper ends of the front legs, rearwardly extending horizontal arms on the lower ends of the front legs, said horizontal arms having rear ends, vertical rear legs having upper ends and lower ends, the lower ends of the horizontal arms being secured to the lower ends of the rear legs, the upper ends of the rear legs being laterally spaced from said handle loop, laterally inwardly and downwardly declining arms on the upper ends of the rear arms, said declining arms having lower ends disposed behind said front legs, lateral outwardly

projecting arms on the lower ends of the declining arms, said lateral arms having free laterally outward ends having attaching eyes thereon disposed behind the rear legs, junctures connecting the lower ends of the declining arms with said lateral arms, said junctures constituting abutments, said holding member being yieldably and rearwardly tensioned toward said abutments.

3. In a rack of the character described, a holding member comprising a pair of front legs having lower ends and upper ends, a handle loop connecting and extending 10 rearwardly from the upper ends of the front legs, rearwardly extending horizontal arms on the lower ends of the front legs, said horizontal arms having rear ends, vertical rear legs having upper ends and lower ends, the rear ends of the horizontal arms being secured to the lower ends of the rear legs, the upper ends of the rear legs being laterally spaced from said handle loop, laterally inwardly and downwardly declining arms on the upper ends of the rear arms, said declining arms having lower ends disposed behind said front legs, lateral outwardly 15 projecting arms on the lower ends of the declining arms, said lateral arms having free laterally outward ends having attaching eyes thereon disposed behind the rear legs, junctures connecting the lower ends of the declining arms with said lateral arms, said junctures constituting abutments, said holding member being yieldably and rearwardly tensioned toward said abutments, said declining arms and said lateral arms being angulated in forward and laterally inward directions out of the plane of said 20 rear legs.

4. In a rack of the character described, a holding member comprising a pair of front legs having lower ends and upper ends, a handle loop connecting and extending forwardly from the upper ends of the front legs, rearwardly extending horizontal arms on the lower ends of the front legs, said horizontal arms having rear ends, vertical rear legs having upper ends and lower ends, the rear ends of the horizontal arms being secured to the lower ends of the rear legs, the upper ends of the rear legs being laterally spaced from said handle loop, laterally inwardly and downwardly declining arms on the upper ends of the rear arms, said declining arms having lower ends disposed behind said front legs, lateral outwardly projecting arms on the lower ends of the declining arms, said lateral arms having free laterally outward ends having attaching eyes thereon disposed behind the rear legs, junctures connecting the lower ends of the declining arms with said lateral arms, said junctures constituting abutments, said holding member being yieldably and rearwardly tensioned toward said abutments, the front legs of said holding member being normally rearwardly inclined with respect to said rear legs.
